CLAIM

The ornamental design for a holder for individual jelly cups, as shown and described.

DESCRIPTION

FIG. 1 is a perspective view of a holder for individual jelly cups, showing my new design, the broken lines indicating two jelly cups supported on two of the horizontal pins being for illustrative purposes only; FIG. 2 is an elevational view of one end, the opposite end being a mirror image thereof; FIG. 3 is an elevational view of one side, the opposite side being a mirror image thereof; FIG. 4 is a top plan view; and, FIG. 5 is a bottom plan view.

FIG. 1

FIG. 2

FIG. 3

FIG. 4

FIG. 5
